UNITED STATES PATENT OFFICE.

WILLIAM M. JONES AND D. W. HALL, OF HORICON, WISCONSIN, ASSIGNEES,
BY MESNE ASSIGNMENTS, OF W. M. JONES AND S. E. TYLER.

IMPROVEMENT IN SEEDING-MACHINES.

Specification forming part of Letters Patent No. 36,159, dated August 12, 1862; Reissue No. 3,197, dated November 17, 1868.

DIVISION A.

To all whom it may concern:

Be it known that we, WILLIAM M. JONES and D. W. HALL, both of Horicon, in the county of Dodge and State of Wisconsin, have, by assignment duly recorded in the Patent Office, become the owners of the whole right to a certain new and Improved Seeding-Machine for which Letters Patent of the United States were granted to WILLIAM M. JONES and S. E. TYLER, August 12, 1862; and we do hereby declare that the following is a full, clear, and exact description of the same, reference being had to the accompanying drawing, forming a part of this specification, in which—

Figure 1 represents a transverse vertical section of our seeding-machine, the line $x x$, Fig. 2, indicating the plane of section. Fig. 2 is a plan or top view of the same. Fig. 3 is an edge view of the seed-distributing cylinder and the semi-cylinder. Fig. 4 is a detached longitudinal section of the scattering-boards. Fig. 5 is a detached sectional view of the driving mechanism which operates the seed-distributing device. Fig. 6 is a detached view of the seed-distributing cylinder, with the semi-cylinder removed. Fig. 7 is a detached perspective view of the seed-distributing cylinder and semi-cylinder. Fig. 8 is a detached plan view of the inner or convex side of the semi-cylinder. Fig. 9 is an edge view of the semi-cylinder detached from the seed-distributing cylinder.

Similar letters of reference indicate corresponding parts in the several figures.

This invention relates to a new and improved machine for sowing seed broadcast; and it consists in a novel and improved means for discharging the seed from the seed box or hopper, whereby the flow of seed may be graduated as desired, so as to sow a greater or less quantity on the same area, and the seed prevented from being broken or bruised in being discharged, and at the same time scattered or sown in a perfect broadcast manner.

To enable those skilled in the art to make and use this invention, we will proceed to describe it with reference to the drawings.

A represents a rectangular frame, which is

mounted on two wheels, B B', placed loosely on arms or axles $a a$. C is a seed-box or hopper, which extends the whole width of the frame A, and is connected at its back part by hinges b to a box, D, which is secured permanently to the frame A, and also extends its whole width, so that the seed-box C, when closed down upon it, will register therewith, the two forming one box, in which the seed-distributing mechanism is placed.

E is a shaft, which runs longitudinally through the box D, and is allowed to slide in its bearings in a longitudinal direction. This shaft, near one end, is provided with a square, c , on which a clutch, F, is fitted, said clutch being furnished with ratchet-teeth at one side. This clutch has a lever, G, connected with it, against which a spring, d , bears, the spring having a tendency to keep the clutch engaged with ratchet-teeth on a collar or sleeve, e , which is placed loosely on the shaft E. A pinion, f , attached to said sleeve gears into teeth g on the hub of the wheel B'.

N is a hub-plate, furnishing bearings for the axle of the wheel B' and the sleeve-pinion f . It is semicircular in shape, and extends above the pinion, forming a covering, as shown in Fig. 2, for the same, to protect it from being clogged by the falling dirt from the wheel B' as the latter moves over the ground. When the clutch F is engaged with the collar e the shaft E will be rotated from the wheel B' as the machine is drawn along, and said shaft may be rendered inoperative at any time, or prevented from rotating, by throwing the clutch F out of gear with the sleeve e , as will be fully understood by referring to Fig. 5.

H is a lever, which is connected to the shaft E, for the purpose of moving it in a longitudinal direction. The outer part of this lever projects over the front part of the frame A, and may be secured at any desired point by a pin, h , which passes through it and into any one of a series of holes, i , made in the front cross-bar, j , of the frame A. The object of thus adjusting or moving the shaft E will be presently explained.

On the shaft E there is placed and permanently attached a cylinder, I, which has a se-

ries of buckets, *k*, attached to it. These buckets extend outward to the periphery of the cylinder *I*, and on the buckets there is fitted a head, *J*, which is formed of a circular plate or disk, having slots made in it corresponding to the shape of the buckets, and a central hole, to allow the buckets and shaft to pass through it, the head fitting snugly to the buckets and shaft, but the latter at the same time being allowed to slide freely through it. By these means a series of seed-cells is formed between the head *J*, the end of cylinder *I*, and two adjoining buckets; and by imparting to the shaft a longitudinal motion the size of these seed-cells can be increased or decreased at pleasure. In order to effect this purpose without crushing or bruising the seed, it is essential to have the disk so arranged that no portion offers a place to the seed to rest upon, and that it passes into the cells and out of them without the liability of crushing the seed.

K represents a curved plate of semi-cylindrical form, which covers the upper part of the cylinder *I* and buckets *k*. This semi-cylinder is secured to the upper part of the box *D*, and it has a square opening, *l*, made in it, as clearly shown in Figs. 7 and 8.

The inner surface of the semi-cylinder *K* is not uniform, a longitudinal groove or recess, *m*, being made in it to receive a curved plate, *L*, which may be termed a "gate," and which is allowed to slide in the semi-cylinder. This gate is provided with a ledge, *n*, at its inner side, which fits in a groove, *o*, made circumferentially in the cylinder *I*, and thereby causes the gate to be connected to said cylinder, so as to move with it.

The head *J* is not allowed to slide or move with the shaft *E*, but rotates with it. It is prevented from sliding with the shaft *E* in consequence of having its periphery fitted in a groove, *p*, in the inner surface of the semi-cylinder *K*, near one end of it.

When the gate *L* is fitted in the semi-cylinder *K* the inner surface of the latter and gate form a curved surface concentric with the cylinder *I* and buckets *k*, as shown clearly in Figs. 1, 3, and 9. Its edge is flush with the edge *k** of the solid part of the cylinder, (see Fig. 6,) and if said cylinder is moved toward the head *J* the gate moves with it. Without the gate, if the cylinder is moved toward the stationary head, the solid part of the same gradually comes opposite the opening *l*, and moves in the seed, and the seed is liable to get bruised. By the use of the gate that portion of the solid part of the cylinder which otherwise would move in the grain is covered, and nothing moves in the grain except the edge of the buckets, and that portion of the buckets opposite the opening will readily fill with grain or corn without any danger of bruising the same.

The semi-cylinder *K* is provided with a chambered recess, *n'*, above the opening *l*, where the edges of the buckets pass under, so as to leave a certain space between the circumfer-

ence of the working portion of the buckets and the inner surface of the semi-cylinder. By this space the seed which is carried up by the buckets is prevented from being crushed.

In the bottom of the seed-box *C* there are placed double inclined planes *g g*, which form a bottom for the same, and cause the seed to be presented or conducted to the opening *l* in the semi-cylinder *K*, as will be seen by referring to Fig. 2; a space being allowed between the ends of the inclined planes for the seed to drop into the opening.

To the frame *A* there is attached a series of frames, *r*, provided with narrow teeth *s*, for covering the seed. Any proper seed-covering device may be employed, and it will be understood that, although only one seed-distributing device is shown and described, a series of them is used, placed side by side.

The lower part of the box *D* is inclined, as shown at *t* in Fig. 1, and immediately below this inclined portion there is placed another inclined board, *u*, the latter being inclined in a reverse position to the former, and so placed in relation to it that it will receive the seed therefrom.

The inclined board *u* has its upper surface or face side provided with a series of grooves, *v*, which radiate from centers *w* at its upper edge, and which are at points in line with the buckets *k*.

The operation is as follows: As the machine is drawn along the shaft *E* is rotated from the wheel *B'*—that is, if the clutch *F* is in gear with the collar *e* of pinion *f*—and the seed in the seed-box *C* passes through the opening *l* in the semi-cylinder *K*, and the buckets *k*, which rotate with the shaft *E*, catch the seed and carry the same upward within the semi-cylinder *K*, and discharge it, as they pass over behind the shaft, on the inclined bottom *t*, and thence on the inclined board *u*, from which it falls upon the ground in a scattered or broadcast state. The head *J*, it will be seen, serves as a partition at one end of the buckets, while the solid portion of the cylinder *I* serves as a partition at the opposite end, and the quantity of seed discharged may be regulated as desired by shifting or moving the shaft *E* in a longitudinal direction, so that the gate *L*, which moves with the cylinder *I*, may cover more or less of the opening *l* in the semi-cylinder *K*. The gate *L* covers the solid part of the cylinder, and when the latter rotates said gate remains stationary, being confined in the longitudinal recess *m*. The seed, therefore, is not allowed to come in contact with the solid part of the cylinder, and the edges of the buckets alone pass through the seed.

By this arrangement, and by the use of the chambered recess *n* above the opening *l*, the seed is prevented from becoming bruised or crushed, and a uniform discharge is insured.

We do not claim the sleeve-pinion with ratchet-teeth on the end of the sleeve, or the clutch and rotating shaft with a pin through the end of the shaft to hold the sleeve-pinion

in place, as this combination has been used before this invention, for the purpose of disconnecting the shaft from the driving-wheel by disengaging the clutch from the ratchet-teeth on the sleeve.

Having thus fully described this invention, what we claim as new, and desire to secure by Letters Patent, is—

1. The chamber or recess n' , formed on the inside of the cap K, and located between the seed-opening in front of the cap and the top of the cap, to allow the edges of the buckets or partitions to pass up under the cap without injuring the seed, substantially as described.

2. Forming and arranging the cap so that a space shall be left at the rear for the seed to begin to fall from the buckets as soon as they are turned far enough to cause the seed to roll or slide over their edges, substantially as described.
